WINDOW FASTENER

Leon R. McNamara, Rockford, Ill.

Application December 9, 1937, Serial No. 178,849

6 Claims. (Cl. 292—204)

This invention relates to improvements in window fasteners and the general object is to provide a fastener of new and improved construction which not only serves to lock a window closed but also provides a stop for limiting the extent to which either the upper or lower section of the window may be opened.

A more detailed object is to provide a window fastener including a pivoted member hinged along one vertical side edge of the upper window section to swing between one position overlying the lower window section and another position permitting opening of either window section a distance determined by the position of a stop on said member.

The invention also resides in the novel characteristics of the fastener which make for simplicity and ruggedness of construction and contribute to the artistic appearance of the fastener when in use.

Other objects and advantages of the invention will become apparent from the following detailed description taken in connection with the accompanying drawing, in which

Figure 1 is a fragmentary perspective view of the left-hand side portion of a window equipped with a fastener embodying the features of the present invention.

Fig. 2 is a fragmentary plan view with the parts positioned as shown in Fig. 1.

Fig. 3 is a detail view looking from the right in Fig. 2.

Fig. 4 is a fragmentary front elevational view of a window illustrating a different use of the fastener.

Fig. 5 is a section taken along the line 5—5 of Fig. 4.

Fig. 6 is a longitudinal sectional view of a part of the fastener.

Fig. 7 is a view similar to Fig. 2 illustrating different positions of the fastener parts.

While the invention is susceptible of various modifications and alternative constructions, I have shown in the drawing and will herein describe in detail the preferred embodiment. It is to be understood, however, that I do not intend to limit the invention by such disclosure but aim to cover all modifications and alternative constructions falling within the spirit and scope of the invention as expressed in the appended claims.

Referring now to the drawing, the numerals 10 and 11 represent the upper and lower sections of an ordinary window construction, which sections are slidable vertically in a casing 12 so that the

window may be fully closed as shown in Fig. 1 or either section may be opened to any degree desired for ventilating purposes. The frame of the upper section has vertical side members 13 and a horizontal bottom member 14 with an inwardly facing inclined surface 15 which, when the window is fully closed, is wedged against a complementary surface 16 on the upper cross member 17 of the lower window section 11.

In standard window constructions of the above character, the cross bar 14 of the upper section projects inwardly from the inner face of the side member 13 a short distance and provides a narrow ledge 18 so that in the open position of the window, the inner face of the side member is spaced from the outer face of the frame of the lower window section a distance equal to or greater than the width of said ledge (see Fig. 5). The present invention takes advantage of this condition and contemplates a fastener comprising an elongated member 20 hinged along the side member of the upper window section, so that it may be swung inwardly to overlie the lower section (see Fig. 1) for locking the window closed, may be disposed within the space above referred to to permit of limited opening of either section as determined by a stop 21 on the member, and may be swung around the side member as shown in dotted outline in Fig. 1 to permit full opening of the window. In the present instance, the pivoted member comprises a reinforced metal bar narrower than the side member 13 and curled along one side edge to interfit with the curled edge of a bar 22. The curled edges are secured together by a pintle 23 so as to form a hinge joint 24 extending throughout the lengths of the bars along the inner side edge of the frame member 13. The bar 22 is secured against the inner face of the side member 13 by screws 25.

To further reinforce the bar 20, the free edge thereof is formed with a narrow flange 29 and the stop 21 is bent from a separate strip 26 of sheet metal which lies against and is spot welded to the rear side of the bar 20 with the stop projecting through an aperture 27 in the bar. Thus, the stop 21 is generally V-shaped and therefore of rugged construction even though formed of sheet metal. If desired, a block 28 of metal may be secured to the bar 22 in a position to project into the recess defined by the stop when the bar 20 is closed against the bar 22. The block serves to further reinforce the stop 21 when the latter is utilized for limiting partial opening of the window.

Preferably, a metal abutment is provided on 55

the upper surface of the lower window section for coaction with the lower end of the hinged member 20 as with the stop 21. Herein this abutment comprises a plate 30 pivoted on a screw 31 anchored in the frame 17. By gripping an upturned flange 32 or handle, the plate may be swung outwardly from the normal position shown in Fig. 1 to the position of Fig. 7. In the normal position, a flange 33 at the free end of the plate 30 bears against the window casing and definitely locates a tapered boss 34 relative to the hinge axis of the member 20. The boss is struck out of the plate 30 on an arc so as to be received in a curved notch 36 in the lower edge of the member 20. The boss and notch are so positioned that as the member is swung away from the upper section into locking position as shown in Fig. 1, the two window sections are cammed toward each other so as to hold the two tightly together.

20 In the locked position of the fastener, the lower end thereof bears against the plate 30 so that there is no danger of marring the painted surface of the window frame. Owing to the rugged reinforced construction of the member 20 and the substantial length of the hinge 24, it will be apparent that the window will be held effectively in closed position without the use of any other fastening device.

30 The stop 21 is spaced from the lower end of the pivoted member a distance such as to permit partial opening of either window section for ventilating purposes but insufficient to permit of entry of unauthorized persons through the window. Usually this distance is about six inches.

35 To condition the window for such partial opening, the member 20 is closed against the supporting hinge bar 22, the stop 21 projecting inwardly perpendicular to the plane of the window. Either window section may then be opened until the stop 40 and the plate 30 engage as shown in Figs. 4 and 5, the bars 20 and 22 then being disposed between the side members of the two window frames. In this condition, the screws 25 are inaccessible and there is no way by which an unauthorized person, 45 working from the exterior of the building, could release the fastener and gain entry.

When it is desired to fully open the window, the plate 30 is first swung into the position shown in Fig. 7. Then, the pivoted member 20 may be 50 swung into the plane of the bar 22 with the stop 21 projecting toward the window pane out of blocking relation with respect to the lower window section.

It will be apparent from the foregoing that my 55 improved fastener is of inexpensive construction, the principal parts being formed as simple sheet metal parts. The fastener is located in an out of the way position at one side of the window where it usually will be concealed from view by 60 curtains or draperies. Moreover, the parts present a more artistic appearance than fasteners commonly used and may be painted or decorated to conform to the window frames and casing.

I claim as my invention:

65 1. A fastener for a sliding double sectioned window comprising two flat elongated bars hinged together along one side edge, one being adapted for attachment to the inner face of one vertical side member of the upper window section, the other bar having an aperture therein adjacent one end thereon, an elongated strip disposed between said bars and secured to said other bar, and a projection bent from said strip and extending through said aperture to provide

a stop for limiting the degree of partial window opening.

2. The combination with a window having upper and lower sliding sections of an elongated element pivotally supported on one vertical side member of the frame of said upper section to swing inwardly from the upper section with its lower end overlying and disposed adjacent the lower section whereby to hold the window fully closed, a stop projecting from said element and positioned to limit to a predetermined degree the opening movement of the lower window section when the element is swung against the frame of said upper section, an abutment on said lower section underlying said lower end and having an upstanding boss coacting with said element during inward swinging thereof to cam the window sections toward each other.

3. The combination with a window having upper and lower sliding sections of an elongated element pivotally supported on one vertical side member of the frame of said upper section to swing inwardly from the upper section with its lower end overlying and disposed adjacent the lower section whereby to hold the window fully closed, a stop projecting from said element and positioned to limit to a predetermined degree the opening movement of the lower window section when the element is swung against the frame of said upper section, an abutment on said lower section underlying said lower end and having means coacting with said element during inward swinging thereof to cam the window sections toward each other, said abutment being pivoted on said lower section and swingable to carry said cam means out of engagement with said element.

4. The combination with a window having upper and lower sliding sections of an elongated element pivotally supported on one vertical side member of the frame of said upper section to swing inwardly from the upper section with its lower end overlying and disposed adjacent the lower section whereby to hold the window fully closed, a stop projecting from said element and positioned to limit to a predetermined degree the opening movement of the lower window section when the element is swung against the frame of said upper section, an abutment on said lower section underlying said lower end and having means thereon coacting with said element during inward swinging thereof to urge the window sections toward each other and frictionally hold the sections together, said abutment being mounted for movement relative to said lower section into an out-of-the-way position.

5. The combination with a window having upper and lower sliding sections of an elongated element pivotally supported on one vertical side member of the frame of said upper section to swing inwardly from the upper section to a position with its lower end overlying and disposed adjacent the lower section whereby to hold the window fully closed, a stop projecting from said element and positioned to limit to a predetermined degree the opening movement of the lower window section when the element is swung against the frame of said upper section, and a wedge member mounted on said lower window section for movement relative thereto between active and inactive positions and adapted, when in said active position, to engage the lower end of said element and hold the latter wedged in said overlying position whereby to hold the window fully closed.

6. The combination with a window having

upper and lower sliding sections of an elongated element pivotally supported on one vertical slide member of the frame of said upper section to swing inwardly from the upper section to a position with its lower end overlying and disposed adjacent the lower section whereby to hold the window fully closed, a stop projecting from said element and positioned to limit to a predetermined degree the opening movement of the lower

window section when the element is swung against the frame of said upper section, and a friction wedge coacting with said element to hold the latter in said overlying position, said wedge being mounted for movement to an inactive position to permit free swing of said element to all of its positions.
